UNITED STATES PATENT OFFICE

2,222,299

RECIPROCATING SCREEN

Walter J. Parks, Shaker Heights, Ohio

Application July 27, 1937, Serial No. 155,878

7 Claims. (Cl. 209—329)

The present invention relates to reciprocating mechanism wherein a body, such as a screen frame, is caused to have reciprocating motion by means of an actuating mechanism such as a drive shaft and an eccentric.

It is the general object and nature of my invention to eliminate vibrations and vibrating forces set up in such a mechanism by means of compensating for and counter-balancing the mass inertia of the reciprocating body with an opposing mass inertia, and the forces generated in the resilient supports of the reciprocating body with opposing and reacting resilient forces.

My invention is particularly adapted for application to screening apparatus wherein the reciprocating body of the mechanism constitutes the screen frame or screen body, and wherein such reciprocating body is disposed in a horizontal plane and intended for so-called "flat angle" operation.

Briefly outlined, the invention consists of a reciprocating body or screen frame resiliently mounted upon a supporting member or base frame, together with an actuating mechanism comprising a drive shaft and an eccentric, and a counter-balancing mass rotatably mounted upon the supporting member at a point removed from the center of gravity of the mass, and means for connecting the drive shaft and eccentric between the reciprocating body and the rotatable mass, so that the reciprocating or translational movement of the reciprocating body is balanced by the rotational movement of the mass. The invention also includes resilient means connected to the rotatably mounted mass so that the forces generated therein will counteract and counter-balance the forces generated in the resilient mounting of the reciprocating body.

It is an established physical law that a body suspended for rotation about an axis, not at the center of gravity, may be struck at a certain point, termed the center of percussion, without causing any pressure on the axis passing through the point of suspension. The center of percussion may be defined as the point of application of all forces tending to cause a body to rotate about a given axis.

As there is no force, other than the weight of the body, acting through the axis of suspension, when the body is acted on by a force at right angles to the centerline through the axis of suspension and the center of percussion and at the center of percussion, the body may be resiliently supported at this point and no movement of the axis will take place.

For each axis of suspension and a given set of operating conditions the center of percussion will vary but for a given set of conditions and a given axis of suspension the center of percussion will remain in a given location. It is also important to note that if the body is suspended from the center of percussion the original axis of suspension will then become the center of percussion.

The fundamental object and principle of operation accomplished by a reciprocating mechanism embodying my invention is therefore to balance the actuating force applied to and acting through the center of gravity of the reciprocating body having a translational motion by opposing force generated and acting through the center of percussion of the body having rotational motion. Additional objects and advantages shall become apparent as the following description proceeds.

To the accomplishment of the foregoing and related ends, said invention, then, consists of the means hereinafter fully described and particularly pointed out in the claims.

The annexed drawings and the following description set forth in detail certain mechanism embodying the invention, such disclosed means constituting, however, but several of various mechanical forms in which the principle of the invention may be used.

In said annexed drawings—

Fig. 1 is a side elevational view of one form of apparatus embodying the principle of my invention; Fig. 2 is an end elevational view of the apparatus shown in Fig. 1; Fig. 3 is an enlarged, detail sectional view of a portion of the drive shaft and taken substantially along line 3—3 of Fig. 2; Fig. 4 is an enlarged, detail sectional view of the counter-weight mounting and taken substantially along line 4—4 Fig. 1; Fig. 5 is an enlarged, detail sectional view of the connecting rod connection to the counter-weight and taken substantially along line 5—5 of Fig. 1; Fig. 6 is a view similar to Fig. 5, but illustrating an alternative form of construction; Fig. 7 is a side elevational view showing a modified form of construction for apparatus also embodying the principle of my invention; Fig. 8 is an end elevational view of the apparatus shown in Fig. 7; Fig. 9 is a detail view illustrating an alternative form of mounting of the counter-weight shown in Fig. 7, to the base frame; Fig. 10 is a fragmentary, end elevational view of the apparatus shown in Fig. 7, but of the end opposite to that shown in Fig. 8; Fig. 11 is an enlarged, detail sectional view of the mounting of the counter-weight of the apparatus shown in Fig. 7 and taken substantially along line 11—11 of Fig. 7.

line 11—11 thereof; Fig. 12 is a fragmentary side elevational view showing a modified form of construction for the form of apparatus shown in Fig. 7; Fig. 13 is a side elevational view of a third alternative form of construction of an apparatus embodying the principle of my invention; and Fig. 14 is an end elevational view of the apparatus shown in Fig. 13.

Now referring more particularly to Figs. 1 to 6 of the drawings, there is shown therein a supporting member or base frame consisting of the longitudinal channels 1 mounted upon the transverse I-beams 2. A screen frame 3 carrying one or more screen decks such as the decks 4 and 5 is resiliently mounted upon the base frame by means of the rubber blocks 6 secured or otherwise suitably attached to the metal brackets 7 and 8 carried by the frame 3 and the channels 1 respectively.

20 The drive shaft 9 is journaled in the bearings 10, housed in the tubular member 11 which extends transversely to and is carried by the screen frame 3. A drive pulley 12 for attachment to a drive motor (not shown) is mounted on one end of the drive shaft 9. The drive shaft 9 has an eccentric portion 13 upon which the connecting rod 14 is journaled at one end by means of the bearing 15. An eccentric counter-weight 16 is mounted upon the main portion of the drive shaft 9 to counterbalance the eccentricity of the shaft portion 13 and the parts which are eccentrically mounted thereon.

25 The connecting rod 14 is connected at its other end to the wrist pin 16 through the bearing 17. The wrist pin 16 is mounted in the arms 18 extending from the reaction member or counter-weight 19 which in turn is rotatably supported upon the members 1 of the base frame by means of the shaft 20 journaled in the bearings 21.

30 The drive shaft 9 is located substantially at the center of gravity of the screen frame 3. The connecting rod 14 is connected substantially to the center of percussion of the counterweight 19 which has its axis of rotation or center of 35 suspension on the shaft 20. Thus the line of action of the connecting rod 14 passes through the center of percussion of the reaction member or counter-weight 19 and also substantially through the center of gravity of the screen 40 frame 3.

35 Resilient means consisting of the rubber blocks 22 are connected between the counter-weight 19 and the housing 23 which in turn is secured to the base frame members 1. Thus the resilient means consisting of the rubber blocks 22 is located substantially in line with the center of 45 percussion of the counter-weight 19 and the line of action of the connecting rod 14.

40 The lines *a*, *a*, in Fig. 1 represent the line of action of the resilient forces generated in the rubber mounting 6 on the screen frame 3. The line *c* represents the line of action of the connecting rod 14 and of the resilient forces generated in the rubber mountings 22. By reference to the distances denoted *X* and *Y* respectively, it will be seen that the line of action of the resilient forces generated in the resilient connections or rubber mountings 22 of the counter-weight 19 on the screen body is substantially midway between the lines of action *a* of the forces generated in the resilient supports 6 of the screen frame 3. In this manner, not only are the resilient forces of both the reciprocating bodies or screen frame 3 counterbalanced and opposed by the resilient forces

generated in the resilient supports of the rotatably mounted reaction member or counter-weight 19, but any turning moment or rocking couple tending to have an effect upon the reciprocal movement of the screen frame 3 is 5 eliminated.

The resultant line of motion of the screen frame 3 will be along the line *c* or the line of action of the connecting rod 14. Thus, in order to compensate for the reciprocal movement of 10 the drive pulley 12, the axis of the drive motor should be located at a point along the line D, D which is normal to the line of reciprocal motion *c*.

15 In the alternative form of construction shown in Fig. 6 for the connection of the connecting rod 14 to the counter-weight 19, a rubber bushing 23 is substituted for the anti-friction bearings 17. This rubber bushing is cured to inner and outer metal tubes 24 and 25 which in turn are keyed to the shaft 16 and connecting rod 14, respectively. The rubber bushing 23 will permit the connecting rod 14 to tilt or pivot through the 20 necessary angle of operation.

25 In the form of construction just described, and shown in Figs. 1 to 6 inclusive, the drive shaft, it will be noted, is mounted upon and carried by the reciprocating body or screen frame 3, and thereby increases the total weight of such body, requiring a coincident relative increase in the weight of the reaction member 30 or counter-weight 19. In the form of construction shown in Figs. 7 to 11 inclusive, the drive shaft or actuating mechanism is supported by the reaction member or counter-weight, thus decreasing the total mass of the reciprocating 35 screen body and increasing the weight of the reaction member.

40 Referring more particularly to Figs. 7 to 11, the screen frame 30 is supported by means of the rubber mounting blocks 31 on the stationary base frame 32. The reaction member or counter-weight 33 is rotatably mounted upon the shaft 34 carried by the frame 32 by means of the rubber bushing 35. The drive shaft 36 is journaled in the lower end of the counter-weight 33 and 45 eccentrically connected by means of the connecting rods 37 to the screen frame 30. The connecting rods 37 in this particular instance are in the form of laminated or leaf springs, thus accommodating the lateral movement of 50 the eccentric drive between the points of connection. A resilient mounting 38 consisting of a rubber block connects the lower end of the counter-weight 33 to the housing 39 extending 55 downwardly from the base frame 32.

55 Fig. 9 illustrates an alternative form of mounting for the axis of rotation of the counter-weight 33, and wherein flanges 40 and 41, spaced apart by the rubber mounting 42, are carried by the counter-weight 33 and the base frame 32 respectively. The center of suspension is located between the flanges 40 and 41 and substantially in the center of the rubber mounting 42, as indicated at 43. Compression of the rubber mounting 42 between the flanges 40 and 41 permits the counter-weight 33 to oscillate or rotate about such center of suspension.

60 Again, in connection with the form of apparatus just described and shown in Figs. 7 to 11 inclusive, it will be seen that the line of action *c'* 70 of the connecting rod 37 passes substantially through the center of gravity of the reciprocating body or screen frame 30 and through the center of percussion of the reaction member or counter-weight 33; and that the resilient means connect- 75

ing the end of the counter-weight 33, viz., at a point removed from its axis of rotation, is substantially in alignment with the center of percussion and the line of action c'. Since the drive shaft 36 and the drive pulley 44 move with the counter-weight 33, the axis of the driving motor should be preferably in alignment with the axis of rotation of the counter-weight 33.

In the modified form of construction shown in Fig. 12, the drive shaft 50 is mounted midway between the screen frame 51 and the counter-weight 52 by means of the leaf spring connecting rods 53 and 54, so that the weight of the drive shaft 50 is equally distributed between the two relatively moving bodies. In this latter form of construction, two eccentrics are provided upon the drive shaft 50, and these eccentrics are located 180° apart and each respectively connected to the connecting rods 53 and 54. In this manner, the drive pulley for the drive shaft 50 would not have to be eccentrically mounted on the shaft and therefore would not be subjected to any axial shifting of position, so that the drive motor can be located in practically any desired position.

In the third alternative form of construction, as shown in Figs. 13 and 14, both the reciprocating body and the reaction member are pendantly supported and resilient mountings and connections are eliminated. In this latter form of construction, the screen frame 60 is pendantly supported from the base frame 61 by means of the hangar bars 62 and 63 which are pivoted at their upper ends 64 and 65 respectively to the frame 61 and pivotally connected at their centers of percussion 66 and 67 to the screen frame 60. The reaction member or counter-weight 68 is pivotally connected at 69 to the supporting frame 61 and carries the drive shaft 70 located substantially at its center of percussion. A connecting rod 71 is eccentrically connected to the drive shaft 70 at one end and pivotally connected at the other end as at 72 to the screen frame 60. Here again the line of action c' of the connecting rod 71 passes through the center of gravity of the screen frame 60 and through the center of percussion of the counter-weight 68. The drive pulley 73 mounted on the drive shaft 70 will of course be subjected to axial reciprocation, so that the drive motor should be mounted in alignment with the axis of rotation 69 or center of suspension of the counter-weight 68.

From the foregoing description of the apparatus embodying the principle of my invention, and the explanation of the mode of operation thereof, it will be seen that I have provided means for eliminating vibration in reciprocating mechanisms wherein a reciprocating body having a motion of translation and a second body having a motion of rotation are counter-balanced by means of actuating forces, acting through the center of gravity of the former body and through the center of percussion of the latter body, such actuating forces offsetting and opposing each other so that there are no residual forces or vibrations transmitted to the base structure or supporting member.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:

75 1. In a reciprocating mechanism, the com-

bination with a frame, a body resiliently supported on said frame, a mass oscillatably mounted on said frame at a point removed from the center of gravity, said point being so positioned that the center of percussion of said mass is located at one end thereof, actuating means adapted to impart reciprocating movement to said body connected between said body and mass at substantially the center of percussion of the latter with respect to its axis of oscillation, and resilient means connecting said mass to said frame in substantial alignment with the line of connection of said actuating mechanism with the body and mass.

2. In a reciprocating mechanism, the combination with a frame, a body resiliently supported on said frame, a mass oscillatably mounted on said frame at a point removed from its center of gravity, said point being so positioned that the center of percussion of said mass is located at one end thereof, actuating means adapted to impart reciprocating movement to said body connected between said body and said mass at substantially the center of percussion of the latter with respect to its axis of oscillation, a bracket carried by said frame and resilient means interposed between said bracket and mass in substantial alignment with the line of connection of said actuating means with the body and mass, and so positioned as to be in shear. 30

3. In a reciprocating mechanism, the combination with a frame, a body resiliently supported on said frame, a mass oscillatably mounted on said frame at a point removed from the center of gravity, said point being so positioned that the center of percussion of said mass is located at one end thereof, actuating means carried by said body adapted to impart reciprocating movement to said body connected between said body and mass at substantially the center of percussion 40 of the latter with respect to its axis of oscillation, and resilient means connecting said mass to said frame in substantial alignment with the line of connection of said actuating mechanism with the body and mass. 45

4. In a reciprocating mechanism, the combination with a frame, a body resiliently supported on said frame, a mass oscillatably mounted on said frame at a point removed from its center of gravity, said point being so positioned that the center of percussion of said mass is located at one end thereof, actuating means carried by said body and located substantially at the center of gravity thereof adapted to impart reciprocating movement to said body connected between said body 55 and mass at substantially the center of percussion of the latter with respect to its axis of oscillation, and resilient means connecting said mass to said frame in substantial alignment with the line of connection of said actuating mechanism with the body and mass. 60

5. In a reciprocating mechanism, the combination with a frame, a body resiliently supported on said frame, a mass oscillatably mounted on said frame at a point removed from its center of gravity, said point being so positioned that the center of percussion of said mass is located at one end thereof, a drive shaft journaled in said frame, and a longitudinally rigid connecting arm eccentrically connected at one end to 70 the drive shaft and at its other end to substantially the center of percussion of said mass with respect to its axis of oscillation and resilient means connecting said mass and frame in substantial alignment with the line of connection of 75

the connecting arm with the shaft and mass, and so positioned as to be in shear.

6. In a reciprocating mechanism, the combination with a frame, a body resiliently supported on said frame, a mass oscillatably mounted on said frame at a point removed from its center of gravity, said point being so positioned that the center of percussion of said mass is located at one end thereof, longitudinally rigid connecting arms extending toward each other from substantially the center of percussion of said mass with respect to its axis of oscillation and from substantially the center of gravity of said body, respectively, a drive shaft eccentrically carried by adjacent ends of said arms, and resilient means connecting said mass to said frame in substantial alignment with the line of connection of said connecting arms with the body and mass.
- 10 7. In a reciprocating mechanism, the com-

binations with a frame, a body resiliently supported on said frame, a mass oscillatably mounted on said frame at a point removed from its center of gravity, said point being so positioned that the center of percussion of said mass is located at one end thereof, a drive shaft carried by said mass and located substantially at the center of percussion of the latter with respect to its axis of oscillation, a longitudinally rigid connecting arm eccentrically connected at one end to the drive shaft and at its other end to said body at a point substantially in alignment with the center of gravity thereof and said center of percussion and resilient means interposed between the frame and mass in substantial alignment with the line of connection of the connecting arm with the shaft and mass, and so positioned as to be in shear.

WALTER J. PARKS. 20
